LAMP BASE

Earl Van Deusen, Seattle, Wash.

Application November 21, 1949, Serial No. 6,163

Term of patent 7 years

(Cl. D48—20)

To all whom it may concern:

Be it known that I, Earl Van Deusen, a citizen of the United States, residing at Seattle, county of King, and State of Washington, have invented a new, original, and ornamental Design for Lamp Base, of which the following is a specification, reference being had to the accompanying drawing, forming a part hereof.

In the drawing:

Fig. 1 is a side elevational view of a lamp base, showing my new design, and

Fig. 2 is a bottom plan view thereof.

The device is uniformly circular about a vertical axis.

I claim:

The ornamental design for a lamp base, as shown and described.

EARL VAN DEUSEN.
